UNITED STATES PATENT OFFICE.

RICHARD LYDSTONE SMALLWOOD, OF TORONTO, ONTARIO, CANADA.

CABLE CONVEYER SPROCKET.

Application filed June 20, 1927, Serial No. 200,156, and in Canada March 1, 1927.

This invention relates to a cable conveyer sprocket as described in the present specification and illustrated in the accompanying drawings which form part of the same.

5 The invention consists essentially of the novel features pointed out broadly and specifically in the claims for novelty following a description containing an explanation in detail of an acceptable form of the invention.

10 The objects of the invention are to provide a cable conveyer sprocket so built that it will retain the conveyer cable thereupon in case the usual cable button engaging the usual gap slips over the cable; to provide 15 wearing parts which are easily assembled upon and removed from the sprocket; and generally, to manufacture an efficient and improved gap wheel capable of accomplishing the aforesaid purposes.

20 In the drawings, Figure 1 is a fragmentary side elevation view of the sprocket, parts being shown in section;

Figure 2 is a section taken on line 2—2 25 in Figure 1;

Figure 3 is a cross section of the wheel rim;

Figure 4 is a front elevation view of the 30 T-bolt fastening the renewable groove segments to the wheel body;

Figure 5 is a side view of Figure 4;

Figure 6 is a fragmentary bottom plan view of the rim showing the bolt slots;

Figure 7 is a fragmentary side sectional 35 view of the removable segments showing the bolt slot;

Figure 8 is a bottom plan view of Figure 7.

40 Like numerals of reference indicate corresponding parts in the various figures.

Referring to the drawings, 10 is the sprocket, having the rim 11, the hub 12, and the usual spokes 13, the hub and spokes forming the web section of the sprocket.

45 The rim is formed with the desired number of gaps 14 sized to receive and enclose the spaced buttons 15 of a conveyer cable 16, the cable engaging the detachable grooved segments 17. The rim, where cut off to provide each of the gaps 14, is formed with the horizontally-arranged bottom flange 18 and

the vertically-arranged flanges 19. To each of the vertically-arranged flanges 19 is detachably fastened a wearing plate 20, the plate being formed with the projecting lug 55 or portion 21 engaging a suitably-sized groove depressed into said flange 19; the wearing plates are fastened in their operative position by means of suitable bolts 23, the plate being counter-sunk to receive the head of each of said bolts, as best shown in Figure 1.

The rim extends out on each side to form flared out flanges 25 and a relatively wide substantially semi-circular groove 26 65 sized to receive and hold the button therewithin should it slip over the cable. The buttons are spaced along the cable to engage the gaps as the wheel rotates, but should one button slip over the cable, the following 70 button would engage the enlarged groove 26 and the cable would not be thrown off the wheel.

The detachable segments 17 are formed with the substantially semi-circular recess 75 27 sized to receive or be engaged by the cable, the segments extending between the gaps.

The segments are secured to the rim by means of the T-headed bolts 27. The rim 80 has the rectangular holes or slots 28 sized to allow clearance for the introduction therethrough of the T-bolts; the detachable segments have rectangular slots 29 terminating in a rectangular cross hole 30 having the 85 recess 31 sized to receive the head of one of the T-bolts. The recess 31 forms means of locking each bolt against rotation while its nut is tightened against the under side of the rim.

90 The segments, which extend between the gaps, are made approximately as long as the clear distance between any two gaps and the wearing plates 20, once secured in position, form means of preventing any longitudinal movement of the segments relative to the rim.

What I claim is:

1. A cable conveyer sprocket comprising 100 a web section, and a plurality of rim sections spaced to provide gaps therebetween adapted to receive the cable buttons, said

rim sections terminating in vertically-arranged flanges having each a horizontally-arranged recess, and a button wearing plate detachably secured upon each of said flanges and having a lug engaging said recess.

2. A cable conveyer sprocket comprising a web section, and a plurality of rim sections spaced to form gaps therebetween

adapted to receive the conveyer cable buttons, wearing plates secured in said gaps, and detachable grooved cable segments secured upon said rim sections and substantially engaging at the ends thereof two of said wearing plates.

Signed at the city of Toronto, May, 1927.

RICHARD LYDSTONE SMALLWOOD.
